United States Patent Office.

CYRUS W. SALADEE, OF CIRCLEVILLE, OHIO.

Letters Patent No. 86,180, dated January 26, 1869.

IMPROVEMENT IN COLLARS.

The Schedule referred to in these Letters Patent and making part of the same.

To all whom it may concern:

Be it known that I, CYRUS W. SALADEE, of Circleville, in the State of Ohio, have invented a new and improved Mode of Making Paper Collars; and I do hereby declare that the following is a full, clear, and exact description thereof, reference being had to the accompanying drawings, and to the letters of reference marked thereon.

The nature of my invention consists in the application, to the inside surface of turn-down paper collars, of a thin sheet of paper, of any appropriate design and color, the turn-down portion of the collar being perforated in any fancied design, through which perforations the finished surface of the colored paper applied on the inside may be exposed, to produce an ornamental effect; or, when a full cravat is used, the fabric composing it will be exposed through these perforations with the same ornamented result.

I purpose manufacturing these collars in a great variety of design, both as to the style and figure of the paper or fabric used on the inside surface of the collar, the shape of the perforation made through the turn-down side of the same to be varied to suit the demand of trade or fashion.

For example, these perforations may consist of a star, an anchor, square and compass, three links, or the emblem of any other secret order, or emblem of military rank, and I may make them omitting the colored or finished paper on the inside surface, and perforate the turn-down side in such manner as to expose through it any printed design upon the inside of the collar, it being so arranged as to register with the perforation on the outside, and thus to expose to view, through the perforations, any design I may print on the inside of the collar, and which arrangement will admit of an almost endless variety of design, where the collar is worn with the "butterfly" neck-tie.

In the drawings—

Figure 1 represents the inside surface of a turn-down collar, before it is folded, and shows the colored-paper

finish, as above described, and also the perforations D, through which the design of the figure or color of the paper is seen, when in use.

Figure 2 represents the same collar, turned down and in position, with "butterfly" neck-tie, and shows the design of the colored paper through the perforations D.

Figure 3 represents the same collar, with full cravat, and exposing to view, through the perforations D, the figure or color of the cravat.

Figure 4 represents the same collar, spread out, (inside view,) showing the printed design hereinbefore described; also, perforations C C, for the reception of the ends of the "butterfly" neck-tie.

Figure 5 represents the same collar, in position, with "butterfly" neck-tie, and exposing, through the perforation D, the design printed on the inside of the collar.

Having thus fully described the nature and object of my invention,

What I claim as new, and desire to secure by Letters Patent, is—

1. A collar, whose inner surface is ornamented by printing, painting, stamping, or embossing any figure or design thereon, or by attaching thereto a fabric so treated, and whose outer or turn-down portion is perforated with suitably-shaped openings, substantially as shown and described.

2. A collar, whose turned-down or exposed surface is provided with openings or perforation therein, through which the neck-tie or ornamented neck-band is exposed, to produce an ornamental effect, substantially as shown and described.

In testimony that I claim the above-described mode of making paper collars, I have hereunto signed my name, this 4th day of January, 1869.

CYRUS W. SALADEE.
